[54] THREE DIMENSIONAL COORDINATE
DIGITIZER

[75] Inventor: David L. Davies, Glastonbury, Conn.

[73] Assignee: Micro Control Systems, Inc., Vernon,
Conn.

[**] Term: 14 Years

[21] Appl. No.: 604,854

[22] Filed: Apr. 27, 1984

[52] U.S. Cl. D14/107

[58] Field of Search D14/100, 107, 114;
33/1 M, 1 CC, 18.1, 432, 503, 504

CLAIM

The ornamental design for a three dimensional coordinate digitizer, as shown and described.

DESCRIPTION

FIG. 1 is a front perspective view of the three dimensional coordinate digitizer embodying my new design; FIG. 2 is a front elevational view thereof; FIG. 3 is a bottom plan view thereof; FIG. 4 is a top plan view thereof; FIG. 5 is a rear elevational view thereof; FIG. 6 is a side elevational view of the three dimensional coordinate digitizer of FIG. 1; and FIG. 7 is an opposite side elevation view thereof.

FIG. 1

FIG. 3

FIG. 4

FIG. 5

FIG. 6

FIG. 7
